Ind., a corporation of Indiana

Application February 16, 1935, Serial No. 6,780

32 Claims. (Cl. 221—95)

My invention relates to liquid dispensing devices, and more particularly to gasoline dispensing installations.

One of the objects of my invention is to provide a novel type of dispensing device for controlling the liquid flow through the dispensing line from a point remotely situated with respect to the pumping unit itself, and preferably from the nozzle end of the dispensing unit and in such a manner that liquid to be dispensed is utilized as a means for transmitting energy from the nozzle end upon the manual actuation of control means, to control the dispensing flow both in starting and stopping of the flow.

Yet another object of my invention resides in providing a liquid dispensing device including a dispensing line terminating in a dispensing conduit provided with a control nozzle, and particularly wherein the terminal portions of the dispensing line comprises a flexible hose with a control nozzle, and wherein remote control mechanism for controlling both the starting and stopping of the dispensing flow is located at the nozzle, and wherein said control mechanism is adapted to start and stop the dispensing flow independent of any movement of the flexible hose, or independent of any encumbering devices extending longitudinally of the hose, such as Bowden wires, hydraulic tubes, air tubes, electrical connections and the like.

Yet another object of my invention resides in providing a remote control mechanism for starting the flow in the dispensing line of a dispensing mechanism wherein a column of liquid in at least a portion of the dispensing line is utilized as a means for transmitting pressure to an actuating means for controlling the dispensing flow.

Yet another object of my invention resides in providing a remote control mechanism for a liquid dispensing device having a flexible hose terminating in a nozzle wherein the column of liquid in the flexible hose is utilized for transmitting energy from a manually actuatable device disposed at the nozzle, to control mechanism for starting the liquid flow and/or for stopping the liquid flow.

Yet another object of my invention resides in providing control means at the nozzle end of a liquid dispensing device wherein a static column of liquid in the dispensing line is utilized as a medium of power transmission from the nozzle end of the line to a control device for governing the dispensing flow.

Yet another object of my invention resides in providing a remote control mechanism for a liq-

uid dispensing device wherein control means is provided at the nozzle end of the dispensing line, and wherein said control means is manually actuatable at desired times and utilizes, as an energy transmission means, a static column of liquid in the dispensing line, and also utilizes a moving column of liquid in the dispensing line for controlling the dispensing operation.

Yet another object of my invention resides in providing a liquid dispensing device wherein the dispensing line terminates in a control nozzle and wherein manually operable remote control means is provided at the liquid dispensing nozzle and comprises a plurality of means, one of which, by its actuation, utilizes the stationary liquid present after the dispensing operation has terminated, as a motion transmitter for actuating a control device to start the dispensing operation and wherein another one of said control means is utilized during the dispensing flow and utilizes the moving column of liquid in the dispensing line as a motion transmitting means for actuating the control member to stop the dispensing flow.

Yet another object of my invention resides in providing a liquid dispensing device with a control nozzle having a manually actuatable device including a plunger or other liquid forcing means adapted to displace more or less the column of liquid in the liquid dispensing line and by such liquid displacement, to actuate a displaceable control mechanism at another portion of the line to start the liquid flow and/or to control the dispensing operation.

Yet another object of my invention resides in providing a dispensing device adapted to dispense exact and predetermined quantities of liquid, as for instance, one gallon, no more or no less, or one dollar's worth of liquid, no more or no less, wherein the control mechanism is accomplished from the nozzle end of the mechanism by the manually actuatable control means situated there, and wherein the dispensing liquid itself is utilized as a motion transmitter for starting and stopping the dispensing operation and in a manner so that the exact amount or volume of liquid may be dispensed from a remote control point and after liquid dispensing has begun. In short, any exact amount or volume of liquid may be dispensed from the nozzle end, the selection being made at any desired time after the dispensing has been initiated.

Yet another object of my invention resides in providing a novel type of hydraulic control for a liquid dispensing device in the manner illus-

trated and described, in the attached specification and drawings.

These and other objects of my invention will be apparent from a perusal of the following specification when taken in connection with the following drawings, wherein

Fig. 1 is an elevational view of one form of my dispensing mechanism;

Fig. 2 is a diagrammatic view of the dispensing line with the housing removed;

Fig. 3 is a vertical sectional view of the top portion of the pump showing the control and nozzle valves with the siphon control mechanism;

15 Referring now to the drawings in detail, I have illustrated my invention as applied to a generally conventional type of pump, which includes a housing or pedestal 2 of any desired construction, shape or size, which housing or pedestal, as is well known in the art, comprises a housing for the supply pipe 4 adapted to be connected to a source of liquid to be dispensed, such as a gasoline or other liquid-containing reservoir. A conduit 4 connects to the inlet side of the pump 6 20 or other liquid-forcing means, which, in the present instance, is a rotary pump adapted to be driven by a motor 8 by power transmission means 10.

30 The motor 8 is provided with any type of switch 12 adapted to be controlled by a rod 14. The discharge side of the pump may be connected to any type of air separator 16 which is adapted to discharge into a dispensing pipe 18 forming a part 35 of the dispensing line, which latter, in turn, discharges into the liquid measuring device preferably comprising any type of meter 20. In addition, the pump is provided with the usual by-pass line having a suitable spring-loaded valve, which valve is adapted to open upon the creation 40 of a predetermined pressure in the line such as is created when the dispensing control valves in the line are closed, whereby the pump may continue to operate by by-passing the liquid through its valved by-pass line, as is well known 45 in the art.

50 The meter 20 may be of any desired well-known construction and is preferably of the liquid displacement type. I prefer to use any of the present commercial type of Bowser meters which 55 are well known in the art. The bowl of the meter is shown in the dotted lines in Fig. 1. In general, it might be stated that this type of meter comprises a sequence of liquid displacement cylinders in which operate pistons. The liquid under pressure, flowing into the meter, 60 will operate the pistons in succession to rotate a shaft, which shaft, in turn, operates any type of clock mechanism to indicate at any instant, the amount of liquid dispensed.

65 As one type of means for controlling the flow of liquid passing through the dispensing line, I provide a control valve which in the present instance I preferably place in the conduit 18, immediately at the outlet of the meter. This control valve comprises a coupling 22 connected to the discharge pipe for the meter 20, and providing an internal valve seat 24. In addition, the coupling 22 is formed with an extension in the shape of a housing 26, the upper portion of 70 which is provided with a discharge coupling 28. A control valve 32 is constructed and arranged to seat against the valve seat 24, the construction being such that the discharge of the liquid from the meter into the housing 26 tends to 75 seat the valve, whereby the flow of liquid will

tend quickly and with a minimum of operating exertion, to seat the valve 32. Valve 32 is provided with a stem 34 which extends into a substantially circular conduit 36, formed by a partition 38. The stem 34 is provided at its upper end with a plunger 40 adapted when moved downwardly, to open the valve 32.

5 The stem 34 has at preferably its central portion, a grooved yoke 42 in which ride pins 44 mounted on a lever 46 pivoted to the shaft 48, which is mounted in the housing 26. Also fast to the shaft 48 is an arm 49 which carries at its outer end the rod 14 extending downwardly to actuate the motor switch 12. The outer end of lever 49, has connected thereto at one end, a spring 50, the opposite end of which spring is stationarily mounted in the housing 26. The spring 50 tends to close the valve 32. Means hereinafter referred to is provided for preventing the spring 50 closing the valve 32 except at predetermined, selected times. Means hereinafter referred to is provided so that the pump will not be put into operation until the valve 32 has been opened, and since there will be no liquid pressure against the valve 32, when it is being opened, 25 the power required to open said valve 32 is equal to the tension of the spring 50, which will not exceed a predetermined pressure, for example, 12 pounds, more or less.

30 Means is provided, in my invention, for controlling the dispensing operation, and in particular, means is provided for opening the control valve and/or also for starting the pump motor from the nozzle end of the dispensing outfit. Means is also provided, actuated and controlled 35 from the nozzle end of the outfit or pump, for causing the automatic closure of the control valve and/or motor pump under the constant will of the operator so that the operator may, during the flow of the liquid as in the dispensing operation, 40 stop the flow and preferably in a manner whereby to dispense a predetermined, exact, volume of liquid measurable in preferably standard unit amounts or sub-multiples or multiples thereof, and wherein the dispensing will automatically 45 stop after said exact unit measurement of liquid has been dispensed. For instance, if, during the dispensing operation, the purchaser should desire five gallons of liquid, the operator may, after starting the flow of the liquid, cause the dispensing 50 of this exact amount and no more, by which arrangement, when a computer clock is utilized with the dispenser, the operator is enabled to dispense gasoline or other liquid purely by reference to monetary value, while at the same 55 time, assurance will be had that the exact volume or amount of liquid corresponding to such monetary value will be dispensed and no more or no less. In other words, since the computer clock is arranged to cooperate with a dispensing mechanism hereinafter described, so as to stop the dispensing flow when a predetermined exact volume of liquid has been dispensed, corresponding to a predetermined and exact price therefor at a basic price per gallon, the liquid to be dispensed 60 can be dispensed accurately by either referring to the amount of liquid sold, or to the price of the liquid sold with the assured knowledge that the exact price and exact amount of liquid corresponding to that price, will be correct.

70 In addition, means is provided so that should the purchaser change his order and desire an additional quantity of liquid, or an additional value of liquid, dispensing may immediately resume by the operation of the control means, and

particularly solely from the nozzle end of the pumping device and without the necessity of the operator approaching the pump pedestal so that upon resumption of such dispensing, and when 5 the exact additional amount of liquid desired has been dispensed, the dispensing operation will again automatically stop.

In my present invention I have preferably provided means for accomplishing this hydraulic dispensing control of the liquid to be dispensed by means of a remote control, preferably located at the nozzle end of the dispensing unit. Specifically, I have accomplished this remote control of the dispensing flow by the direct utilization 10 of the column of liquid in the dispensing line in connection with associated devices so that upon the predetermined operation of manual means, the column of liquid in the dispensing line and preferably a predetermined portion thereof, will 15 function not only to start the dispensing flow, but will also function to stop the dispensing flow and thereafter, if desired, recommence the dispensing flow. This remote control of the dispensing flow is accomplished without the addition of Bowden 20 wires, air tubes, hydraulic liquid tubes, electric wires or other adjunctive devices extending along the usual flexible hose of the dispensing line. Experience has shown that such adjunctive devices are, from a commercial and practical stand- 25 point, mainly inoperative, or are barred by reason of Fire Underwriters' regulations. For instance, it is well known that the flexible hose portion of the dispensing line tends to stretch considerably after some usage, and hence where 30 Bowden wire controls and/or sealed hydraulic tubes are utilized for the transmission of power from the remote control station at the end of the nozzle to the dispensing control devices, such devices are rendered impractical, due to the need 35 of constant adjustment in order to compensate for the stretching of the hose and/or to compensate for the utilization of the hose stretched to its full length as when dispensing liquid far 40 away from the pedestal, as distinguished from dispensing liquid into a tank relatively close to the base of the pedestal. So also where electrical devices are used, extending along the flexible hose, the utilization therewith of electric switches on the nozzle, or the utilization of electrical wires extending along the hose is barred 45 due to the possibility of the switches sparking, and due to the possibility of the electric wires breaking as a result of continuous flexing, and bending, during use. The compressed air remote 50 control device, while overcoming the former objections, tends to make the dispensing hose slightly bulky and unwieldy.

In carrying out my present invention, the coupling 28 of the housing 26 has attached thereto a rigid portion 52 of the dispensing line, which passes through the housing 2 and connects with the sight glass 54 mounted at the upper portion of the housing, as is well known. This sight glass 54 discharges through an outlet 56 to which is 55 coupled one end of the usual flexible hose 58 as is well known in the art. The opposite end of this flexible hose 58 is provided with a nozzle 60, which has a discharge spout 62 and a nozzle guard 64. A nozzle valve lever 66 is pivoted to the guard as at 68 and adapted to bear against the valve stem 70 of the nozzle valve 72, adapted to be normally seated by means of a spring 74 located within the nozzle 60. Inward movement 70 of the valve 70 is adapted to open the valve 72. 75 In addition, the nozzle is provided with a check

valve or drain valve 76, which is normally forced upon its seat by means of a spring 78. This drain valve or check valve 76 is adapted to close as soon as the flow of gasoline ceases, so as to retain the gasoline within the flexible hose and 5 irrespective of the closure of the nozzle valve 72.

The nozzle is also provided with a relatively small plunger 80, which is adapted to operate in a cylindrical portion 82 of the nozzle 60. This plunger 80 is of cup-leather construction 10 and is mounted on a rod 84 and held in position by two metal discs 86, and the nut 88. The rear end of the plunger assembly is provided with a valve-shaped disc 90 which, in normal position, is held against the seat 92 by means of the 15 spring 94 whereby to prevent leaking and whereby to enable the back stroke of the plunger to be relieved to atmosphere through a passage-way 96, discharging into the nozzle spout 62. The stem 84 is adapted to be pushed inwardly 20 by means of a lever 100 pivotally mounted as at 102 on the nozzle proper. To initiate the flow, the operator operates the lever 100 and releases it. This moves the plunger 80 inwardly and the 25 column of liquid in the nozzle, and also in the flexible hose becomes a medium of transmitting movement to the plunger 40 contained within the housing 26 located at the discharge outlet of the meter.

Operating in conjunction with this housing 26 and particularly in connection with the partition 38 thereof, a valve 104 is provided, which is adapted to be seated by means of a spring 105 so as to close an opening in the partition 38, 30 thereby confining the column of liquid between the plunger 40, that portion of the housing 26 formed by the partition 38, the valve 104, the pipe 52, the flexible hose 58, the nozzle 60 including that portion thereof formed by the closed nozzle valve 72, and the plunger 80. It 35 will thus be noted that due to the arrangement of this check valve 104, and the fact that the nozzle valve is closed, I thus have a sealed column of liquid between this plunger 80 in the nozzle and the plunger 40 in the housing 26. When the plunger 80 moves inwardly, it moves the entire static column of liquid, thereby forcing the plunger 40 downwardly as shown in Fig. 3, and opening the valve 32. Due to the connections hereinbefore described, when the valve 32 is depressed, the arm 46 will be rocked, which will rock shaft 48, which in turn will move inwardly a locking finger or control member 106. When this occurs, pawl 108 under actuation of spring 110, which is fixed to a stationary part, 40 and to an extension 112 of pawl 108, will lock the control finger 106 in its outward position, thus locking the valve 32 in the open position. In addition, movement of the valve 32 downwardly with the consequent rocking of shaft 48 will likewise rock lever arm 49, whereby to shift switch control rod 14 so that the motor switch 45 will close the switch contact at the moment that pawl 108 drops into its locking position, which is preferably after the valve 32 has opened. A slight over-travel is provided for the control finger 106 to assure this condition.

In connection with the hereinbefore described remote control mechanism for the dispensing operation, I may, but not necessarily so, utilize the control mechanism with the type of exact and predetermined quantity or volume dispenser I have disclosed and claimed in applications heretofore filed by me, said applications known 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

as Serial No. 4,674, filed February 2, 1935, and Serial No. 4,675, filed February 2, 1935, in which applications a more complete disclosure of the mechanism thereof is referred to, and particularly in application Serial No. 4,675 aforesaid.

As hereinbefore pointed out, the spring 50 tends to close the valve 32, but is prevented from so doing by the locking pawl 108.

In addition to the means for opening the valve 32 to start the dispensing flow, I have also provided means for stopping the fluid flow, and preferably from the remote control mechanism, in the present instance from the nozzle end of the dispensing unit. In this instance I preferably avail myself of a sudden rise of pressure in the dispensing line, and particularly the sudden rise of pressure occasioned by sudden stoppage of the flow therethrough so that due to a water hammer action set up, the precipitate rise in pressure to a predetermined amount will operate a flexible bellows or sylphon arrangement whereby to actuate associated mechanism for controlling the liquid flow and particularly for closing or permitting the closure of the control valve 32 and/or the closing of the pump.

In the present arrangement, the housing 26 is provided with a displaceable device such as a cylinder piston but preferably a flexible diaphragmatic device preferably in the form of a sylphon or bellows 114, the outer end of which carries a stem 116, normally expanded by means of an internally located spring 118. This stem extends outwardly through the wall of the housing 26 directly into the path of the extension 112 on the pawl 108. The spring 118 is peripherally provided with an adjustment consisting of the bushing threadedly engaging the sylphon housing about the plunger 116 and contacting spring 118. By the arrangement of this displacement device, such for instance as a sylphon bellows, after the dispensing operation has begun, I am enabled to operate the control mechanism for stopping the dispensing flow, by utilization of the moving body of liquid flowing through the flow line, and particularly through the terminal or terminal portion thereof. Specifically, I utilize the momentum of the flow of the gasoline and take advantage of the so-called hammer action for transmitting motion to the actuatable mechanism. In short, by the quick closing and then opening movement of the lever 66 which closes momentarily and then opens the nozzle valve 72, a hammer action is created in the terminal portion of the flow line, which acts upon the collapsible or displaceable member, to-wit: specifically the sylphon bellows 114, whereby to actuate the plunger 116 which will strike the locking pawl 108, pushing it outwardly, thereby releasing the locking control member 106 which will permit the valve 32 to close under the action of the flow of the liquid and the spring 50. After the momentary closing of the nozzle valve 72 to actuate and close the control valve 32 has been accomplished, the dispensing flow will terminate and therefor it is immaterial if the nozzle valve is opened or closed, since the pressure being relieved in the nozzle, the drain valve 76 will close. If it be desired to resume dispensing, the plunger 100 is again actuated as hereinbefore described.

It will be noted that during the dispensing operation the liquid will flow through the meter, flow through the opened control valve 32 and will open the check valve 104 against the tension of

its spring, the liquid flowing thence through the flow line. During this flow the liquid will not pass the plunger 40, but will flow through the open check valve 104. On the other hand, when it is desired to start the flow and the lever 100 is operated, and as a consequence plunger 80 is forced inwardly, the column of liquid being confined by the nozzle valve 72 and by the then closed check valve 104, the liquid will force the plunger 40 downwardly to open the control valve 32. The pressure created by forcing the plunger 80 inwardly is arranged to produce a pressure in the housing 26 of substantially twelve pounds, which is sufficient to open the valve 32 against the tension of the spring 50, since this latter spring is selected as not to have its pressure exceed 12 pounds. The sylphon bellows 114, being adapted to be operated by hammer action pressure, which is somewhat in excess of the customary pre-selected 15 pounds by-pass pressure of the pump by-pass check valve, the sylphon spring 118 will have its pressure adjusted so that the sylphon will operate at an excess of the 15 pounds by-pass pressure, and consequently will not be actuated by the pressure created upon operation of the lever 100. In short, the pressure of the spring 118 or the pressure at which the collapsible device, such as the sylphon bellows, operates, is appreciably higher than the pressure of the spring controlling the valve in the pump by-pass line and is appreciably higher than the pressure created by operating the starting plunger 100. Therefore, when it is desired to start dispensing, the opening of the control valve, as hereinbefore described, will likewise swing the control pawl 106 to the left, or in a counterclockwise direction, which will be sufficient to move this control pawl 106 under the shoulder of the locking pawl 108, which is moved downwardly by means of the spring 110, thereby holding the control valve 32 in an open position and likewise subsequently moving the pump motor switch to a position such as to start the pump. In this connection it will be noted that since the valve 32 is opened prior to the starting of the pump, the opening movement occasioned by the inward movement of the plunger 80 will be sufficient to overcome the spring 50. The control valve, having been opened, it is then held in open position by means of the latch 108. When it is desired to stop dispensing, momentary closing of the nozzle valve, as hereinbefore described, will create a pressure in excess of the pressure of the spring 118 which will thence operate the sylphon to project plunger 116 thereof to the right, whereby to release the latch 108, and since the pump is still operating and creating a flow through the open control valve 32, this valve will close under the pressure of the dispensing flow and also under the pressure of the spring 50.

If desired, instead of closing the control valve at any desired instant, irrespective of the dispensing of an exact or predetermined amount or volume of liquid, I may arrange the control pawl 106 whereby it cooperates with an associated control device, such as disclosed and claimed in my prior applications, Serial No. 4,674 and Serial No. 4,675, and particularly Serial No. 4,675, hereinbefore referred to, in which case the meter is provided with an extension shaft 120 carrying a rotatably driven slotted disc 122 which corresponds to the slotted disc shown in my prior applications, hereinbefore mentioned. In addition, the computing mechanism and associated cooperative mechanism of these two applications may be

utilized in connection with this slotted disc, it being understood, of course, that the remote control devices of said applications are not utilized, but in place thereof, the present disclosed invention is utilized. The slotted disc is utilized in association with the control pawl 106, the valve will close only when a slot in the disc registers with this control pawl 106 so that as the meter shaft rotates, a slot thereof will be brought into registration with the control 106 at a time when an exact, predetermined amount or volume of liquid has been dispensed, and at that time, and no other, the control 106 will be operated to permit and bring about the closing of the control valve 32. In other words, the mechanism will function exactly as the mechanisms in my prior applications Serial No. 4,674 and Serial No. 4,675 function.

It is to be understood, of course, that when the control mechanism is used without the slotted disc construction for delivering predetermined gallonages, as hereinbefore stated, the nozzle valve control lever is operated in a manner quickly to close the nozzle valve to produce the water hammer action. When once closed, obviously the valve can remain closed because the control valve and/or the pump will be practically instantly stopped, however, when the remote control mechanism is utilized with the slotted disc construction hereinbefore set forth, the nozzle valve will be closed momentarily to initiate the subsequent automatic closure of the control valve by the slotted disc mechanism and that after the momentary closure of the nozzle valve, the same will then remain open to continue the dispensing until the control valve is automatically closed at a predetermined gallonage.

What I claim as new and desire to secure by Letters Patent of the United States is:

1. In a liquid dispensing device, the combination with means forming a dispensing line through which liquid is adapted to flow under pressure, a dispensing nozzle on said line and a shiftable control member for said dispensing nozzle, shiftable means for controlling the dispensing flow, and manually operable means actuated from the nozzle end of said line for actuating said shiftable means for starting the dispensing flow, said manually operable means including devices utilizing the liquid in at least a portion of said dispensing line.

2. In a liquid dispensing device, the combination with means forming a dispensing line through which liquid is adapted to flow under pressure, said line terminating in a dispensing nozzle, shiftable means for controlling the dispensing flow, and manually operable means actuated from the nozzle end of said line for shifting said means for starting and stopping the dispensing flow, said manually operable means including devices utilizing the liquid in at least a portion of said dispensing line.

3. In a liquid dispensing device, the combination with means forming a liquid dispensing line through which liquid is adapted to be dispensed under pressure, said line terminating in a dispensing nozzle, shiftable means remotely situated from said nozzle for controlling the dispensing flow through said line, manually shiftable means at said nozzle, and motion transmitting means for actuating the dispensing control means due to the manual actuation of said shiftable means at the nozzle, said motion transmitting means including means for creating relatively different

pressures by the utilization of a portion of the liquid column in said dispensing line.

4. In a liquid dispensing device, the combination of means forming a dispensing line through which liquid is adapted to be dispensed under pressure, control means for starting and stopping the flow through said line, manually actuatable means remotely situated from said control means and located at the nozzle end of said line including means utilizing the movement of the liquid in the flow line for creating a water hammer and actuated thereby for actuating said control means to stop the flow and including means for utilizing the static column of liquid in such flow line for operating the control means to start the flow.

5. In a liquid dispensing device the combination of means forming a dispensing line through which liquid is adapted to be dispensed under pressure, a dispensing nozzle for said line, a manually shiftable valve for said nozzle, dispensing control means for starting and stopping the liquid flow, manually actuatable means disposed at the dispensing nozzle and remote from said control means, and means operated by said manually actuatable means for transmitting pressure through the instrumentality of at least a portion of the liquid flow line for operating the dispensing control means to start and also to stop the liquid flow.

6. In a liquid dispensing device, the combination of means forming a dispensing line through which liquid is adapted to be dispensed under pressure, a shiftable control valve for said line for controlling the dispensing therethrough, dispensing control means for starting and stopping the liquid flow, manually actuatable means disposed at the dispensing nozzle and remote from said control means, and means operated by said manually actuatable means for utilizing at least a portion of the liquid flow line to operate the dispensing control means to start and also to stop the liquid flow.

7. In a liquid dispensing device the combination of means forming a dispensing line through which liquid is adapted to be dispensed under pressure, a shiftable control valve for said line for controlling the dispensing therethrough, dispensing control means for starting and stopping the liquid flow, manually actuatable means disposed at the dispensing nozzle and remote from said control means, and means operated by said manually actuatable means for creating a pressure through the instrumentality of at least a portion of the liquid flow line for starting the dispensing control and for creating a different pressure through instrumentality of at least a portion of the liquid flow line for stopping the liquid flow.

8. In a liquid dispensing device, the combination of means forming a dispensing line through which liquid is adapted to be dispensed under pressure, an actuatable control valve for said line, dispensing control means for starting and stopping the liquid flow, manually actuatable means disposed at the dispensing nozzle and remote from said control means, and shiftable means operated by said manually actuatable means for momentarily stopping the dispensing flow to create a water hammer, and means operable by said water hammer for operating said dispensing control means and shiftable means operable by said manually actuatable means upon the termination of the dispensing flow for bodily moving at least a portion of the dispensing column

in said flow line for actuating said control means to start the liquid flow.

9. In a liquid dispensing device, the combination of means forming a dispensing line through which liquid is adapted to be dispensed under pressure, a pump for forcing liquid through said line, a motor for operating said pump, a switch for operating the motor, said line terminating in a dispensing nozzle, manually actuatable control means located at the nozzle and remote from the pump, and pressure-operated devices operable by pressure created upon the manual actuation of said control means and through the instrumentality of liquid in the flow line for causing the starting and stopping of said pump.

10. In a liquid dispensing device, the combination of means forming a dispensing line through which liquid is adapted to be dispensed under pressure, a control valve for said line adapted to open and close to control the dispensing flow therethrough, said line terminating in a dispensing nozzle, manually actuatable control means located at the nozzle and remote from the valve, and pressure operated devices operable by energy created upon the manual action of said control means located at said nozzle and through the instrumentality of liquid in the flow line for causing the opening and closing of said valve.

11. In a liquid dispensing device, the combination of means forming a dispensing line terminating in a nozzle, a pump for forcing liquid through said line, a valve adapted to control the flow through said line and closing on its seat in a direction with the flow of liquid through said line, spring means for aiding the closure of said valve, control means for said pump, manually actuatable means disposed on said nozzle and pressure operated devices operable by pressure created upon the manual actuation of said actuatable means and through the instrumentality of liquid in the flow line for causing the opening of said valve and thereafter for causing the operation of the pump.

12. In a liquid dispensing device, the combination of means forming a dispensing line terminating in a nozzle, a pump for forcing liquid through said line, a valve adapted to control the flow through said line and closing on its seat in a direction with the flow of liquid through said line, spring means for aiding the closure of said valve, control means for said pump, manually actuatable means disposed on said nozzle and pressure operated devices operable by pressure created upon the manual actuation of said actuatable means and through the instrumentality of liquid in the flow line for causing the opening of said valve and thereafter for causing the operation of the pump and for thereafter causing said pump to stop after said control valve has closed.

13. In a liquid dispensing device, the combination of means forming a liquid flow line through which liquid is adapted to be forced under pressure, an actuatable control valve for said line, said line terminating in a nozzle, means for controlling the liquid flow in said line, manually actuatable means for utilizing a portion of the column of liquid trapped in the line during the standby conditions for operating said control means, and manually operable means for utilizing at least a portion of the column of liquid travelling the same line during dispensing for actuating said control means.

14. In a liquid dispensing device, the combination of means forming a dispensing conduit

through which liquid is adapted to be forced under pressure, manually operable means for stopping the liquid flow in said line whereby to entrap a column of liquid in said line, means utilizing the momentum of said column in order to stop the liquid flow, and shiftable means operable upon the entrapped column of liquid to initiate liquid flow in said line.

15. In a liquid dispensing device, the combination of means forming a liquid conduit through which liquid is adapted to be forced under pressure, an actuatable control valve for said line, manually operable means for stopping the liquid flow in said conduit and for utilizing the momentum of said checked column of liquid to control the liquid flow, and manually operable means for bodily moving a portion of the checked column of liquid in the flow line after dispensing has ceased for starting the liquid flow in said conduit.

16. In a liquid dispensing device, the combination of means forming a dispensing conduit, power operated means for delivering liquid through said conduit under pressure, manually operable means for checking the liquid flow in said line whereby to utilize the momentum of said checked column to control the power operated means, said manually operable means serving to entrap a column of liquid in said line after flow has ceased, and manually operable means for utilizing said entrapped liquid to control said power operated means.

17. In a liquid dispensing device, the combination of means forming a dispensing line, a pump for forcing liquid through said line, said line terminating in a nozzle valve having a manually operable member, a drain valve disposed between said nozzle valve and the end of said nozzle, said nozzle including a spring operated plunger adapted upon movement to bodily move the column of liquid in said nozzle and in said line when said nozzle valve is closed, said dispensing line at a remote point including a control valve, a plunger for operating said control valve, said plunger being operable by the movement of a column of liquid in said line, a spring-operated check valve controlling the by-pass conduit connecting the valve seat of said valve with said conduit around said plunger, spring means for closing said control valve, a pressure-operated device disposed in the conduit on the nozzle side thereof of said second plunger, said device operating at a higher pressure than the spring of said control valve, a control pawl for said control valve, and a locking latch for holding said pawl and the control valve in an open position, said latch being operable by movement of said collapsible device.

18. In a liquid dispensing device, the combination of means forming a dispensing line, a pump for forcing liquid through said line, said line terminating in a nozzle valve having a manually operable member, a drain valve disposed between said nozzle valve and the end of said nozzle, said nozzle including a spring operated plunger adapted upon movement to bodily move the column of liquid in said nozzle and in said line when said nozzle valve is closed, said dispensing line at a remote point including a control valve, a plunger for operating said control valve, said plunger being operable by the movement of a column of liquid in said line, a spring-operated check valve controlling the by-pass conduit connecting the valve seat of said valve with said conduit around said plunger, spring means for closing said con-

trol valve, a pressure-operated device disposed in the conduit on the nozzle side thereof of said second plunger, said device operating at a higher pressure than the spring of said control valve, 5 a control pawl for said control valve, a locking latch for holding said pawl and the control valve in an open position, said latch being operable by movement of said collapsible device, and a pump controlling member and means for operating said 10 pump controlling member from the operation of said control valve, said pump controlling member operating to start the pump after the opening of said control valve and for stopping the pump after the closing of said control valve.

15 19. In a liquid dispensing device, the combination with a pump, a meter, means forming a liquid flow line through which liquid is adapted to be forced for operating said meter, a meter shaft carrying a rotatable control disc having a plurality of control members thereon, a cooperative control member adapted to be actuated upon registration with any of said control members when in registration, a control valve adapted to be operated upon actuation of said co-operative 20 control member, and manually actuatable remote control means at the nozzle end of the dispensing line including means for stopping the dispensing action and including means for conditioning one 25 of said control means to close said valve on registration of certain of said registering control means, and manually actuated means at said nozzle operable after the dispensing has ceased for bodily shifting a portion of the dispensing column, and means actuated thereby for shifting 30 the control valve to open the same.

20 20. In a liquid dispensing device, the combination of means forming a dispensing line through which liquid is adapted to flow under pressure, said line terminating in a dispensing nozzle, 40 means for controlling the dispensing flow, manually operable means at the nozzle end of said line, including a plunger adapted on operation to bodily move the column of liquid in said nozzle and line, and pressure actuated means moved 45 by said column of liquid for actuating the flow controlling means.

21 21. In a liquid dispensing device, the combination with means forming a dispensing line through which liquid is adapted to flow under pressure, an actuatable control valve for said line, means for controlling the dispensing flow, and manually operable means disposed at the end 50 of the dispensing line remote from the flow controlling means, said manually operable means including devices for creating a pressure upon at least a portion of the column of liquid in said line and means actuatable by the movement of said column of liquid to start said flow control means.

22 22. In a liquid dispensing device, the combination of means forming a liquid flow line through which liquid is adapted to be forced under pressure, an actuatable control valve for said line, shiftable means for starting the flow through 60 said line, manually operable means located at the end of said flow line remote from said shiftable means and devices connected thereto adapted upon actuation of said shiftable means to bodily move at least a portion of the column of liquid in said flow line and thereby actuate the shiftable flow control means for starting the liquid flow.

23 23. In a liquid dispensing device the combination of means forming a liquid flow line terminating in a nozzle, a control valve disposed

adjacent the end of the dispensing line, an actuatable means for opening and closing said valve, means for forcing liquid under pressure through said dispensing line, a meter in said line adapted to measure the flow therethrough, 5 means for controlling the flow of liquid through said line, shiftable means adapted to confine a body of the liquid normally flowing through said line, a shiftable device associated with that portion of the line in which the liquid is so entrapped and adapted to be actuated by a water hammer effect produced in the line, means actuated by the shiftable means for operating the fluid control means, a second shiftable means disposed in that portion of the line in which the liquid is entrapped and operatively associated with the liquid control means, and shiftable means associated with the line for manually moving the body of liquid so entrapped to actuate said last mentioned means. 15

24. In a liquid dispensing device the combination of means forming a liquid flow line, means for forcing liquid through said line under pressure, liquid measuring means in said line, said line terminating in a dispensing nozzle, manually 20 actuatable control means for stopping the flow in said line, control means for said line to start and stop the flow, means for entrapping a column of liquid in said flow line, shiftable means disposed in that part of the flow line in which the liquid is entrapped and actuated by a sudden stoppage of flow through said line for actuating control means, additional means disposed in that part of the flow line in which liquid is entrapped and connections therefrom to the flow controlling 30 means and means for bodily moving the column of liquid so entrapped for actuating said second mentioned means, said first mentioned shiftable means in that part of the flow line in which the liquid is entrapped remaining inoperative 35 during the bodily movement of said column of liquid.

25. In a liquid dispensing device the combination of means forming a flow line through which liquid is adapted to flow under pressure, liquid 40 measuring means in said flow line, said flow line terminating in a dispensing nozzle, valve means located adjacent the end of said line for controlling the flow therethrough, operable means thereat for operating said valve, a shiftable device operatively associated with said flow line and adapted to be shifted in response to the flow of liquid therethrough, control means for controlling the flow of liquid through said line and actuated by the shifting of said device, a by-pass line 50 in said dispensing line around said shiftable device to permit the free flow of liquid through the line during the dispensing operation, closure means adapted to close said by-pass after said dispensing operation has ceased, and means for 55 creating a predetermined pressure upon said closure means through the column of liquid in said line for closing the same, said pressure creating means being sufficient to also shift said shiftable device in the line to actuate said control means.

26. In a liquid dispensing device, a dispensing conduit having means at one end thereof for supplying liquid under pressure thereto, a valve located intermediate the ends of said conduit, 70 means operated in synchronism with said valve to control said first named means to supply or to stop supplying fluid to said conduit according to whether said valve is open or shut, means operable in response to a predetermined pressure 75

in the other end of said conduit for opening said valve and maintaining it open, and additional means responsive to a different predetermined pressure in said other end of the conduit for releasing said maintaining means to permit closing of the valve.

27. In a liquid dispensing device, a dispensing conduit having means at one end thereof for supplying liquid under pressure thereto, a valve located intermediate the ends of said conduit, means associated with said valve for controlling said first named means to supply or to stop supplying liquid to said conduit in response to opening or closing of said valve, means operable upon the creation of a predetermined pressure in the other end of said conduit to open said valve and maintain it open, means to prevent the complete closing of said valve except when an exact unit quantity of fluid or multiple thereof has been dispensed through said conduit and additional means responsive to a different predetermined pressure in said other end of the conduit for disabling the maintaining means to condition said valve for closing under control of said preventing means.

28. In a liquid dispensing device, the combination with means forming a dispensing line through which liquid is adapted to flow, shiftable means in said line for controlling said flow, manually operable means in said line at a point remote from said shiftable means and adapted to utilize the liquid in the line between the manually operable and said shiftable means for actuating the shiftable means in response to manipulation of the operable means.

29. In a liquid dispensing device, the combination with means forming a dispensing line through which liquid is adapted to flow, shiftable means in said line for controlling said flow, manually operable means in said line at a point remote from said shiftable means and adapted to utilize the liquid in the line between the manually operable and said shiftable means for actuating the shiftable means in response to manipulation of the operable means, and means under the control of said shiftable means for delivering liquid under pressure to said line.

30. In a liquid dispensing device, the combination with means forming a dispensing line through which liquid is adapted to flow, shiftable means in said line for controlling said flow, manually operable means in said line at a point remote from said shiftable means and adapted to utilize the liquid in the line between the manually operable and said shiftable means for actuating the shiftable means in response to manipulation of the operable means, and means for measuring the liquid flowing in said line.

31. In a liquid dispensing device, the combination with means forming a dispensing line through which liquid is adapted to flow, shiftable means in said line for controlling said flow, manually operable means in said line at a point remote from said shiftable means and adapted to utilize the liquid in the line between the manually operable and said shiftable means for actuating the shiftable means in response to manipulation of the operable means, means under the control of said shiftable means for delivering liquid under pressure to said line, and means operable upon initiation of flow in said line to prevent discontinuation of flow until a predetermined quantity of liquid has passed through the line.

32. In a liquid dispensing device, the combination with means forming a dispensing line through which liquid is adapted to flow, shiftable means in said line for controlling said flow, manually operable means in said line at a point remote from said shiftable means and adapted to utilize the liquid in the line between the manually operable and said shiftable means for actuating the shiftable means in response to manipulation of the operable means, means under the control of said shiftable means for delivering liquid under pressure to said line, displacement measuring means operatively associated with said line for measuring the liquid flowing therein, and means drivingly connected with said measuring means and operable to prevent discontinuation of flow until a predetermined quantity of liquid has passed through the line.

WILLIAM M. CARROLL.
